(57) **CLAIM**

The ornamental design for “signboard”, as shown and described.

DESCRIPTION

FIG. 1 is a perspective view of a signboard showing my new design;

FIG. 2 is a front elevational view of the signboard illustrated by FIG. 1;

FIG. 3 is a side elevational view of the signboard illustrated by FIG. 1;

FIG. 4 is a perspective view of the signboard illustrated by FIG. 1, taken from the side; and,

FIG. 5 is a front elevational view of a signboard shown in an alternate collapsed position.

1 Claim, 5 Drawing Sheets

FIG. 3

UNITED STATES PATENT AND TRADEMARK OFFICE
CERTIFICATE OF CORRECTION

PATENT NO. : Des. 616,029 S

Page 1 of 7

APPLICATION NO. : 29/313697

DATED : May 18, 2010

INVENTOR(S) : Horst-Werner Maier-Hunke

It is certified that error appears in the above-identified patent and that said Letters Patent is hereby corrected as shown below:

Title Page illustrating a Figure should be deleted and replaced with new Title Page illustrating a Figure. (Attached)

Delete drawing Figures 1-5, and substitute the attached drawing Figures 1-5.

Signed and Sealed this

Twenty-seventh Day of July, 2010

David J. Kappos
Director of the United States Patent and Trademark Office
